KEY CONTROLLED CALCULATING
MECHANISM

Samuel Brand, Binghamton, and James M. Cunningham, Endicott, N. Y., assignors to International Business Machines Corporation, New York, N. Y., a corporation of New York

Application April 23, 1942, Serial No. 440,194

12 Claims. (Cl. 235—61)

This invention relates to a key-controlled calculating machine and more particularly to improved mechanism for effecting the entry of data into accumulating mechanisms.

The principal object of the invention is to provide improved storage or data retaining mechanism into which an amount may be entered from a keyboard, digit by digit, and then transferred from the storage device to an accumulator of the type in which all the digits of the amount are entered concurrently.

A further object of the invention is to provide improved data entering mechanism for an accumulator, in which storage devices are provided and controlled alternately by the keyboard, which devices in turn alternately enter their data into the accumulator in such manner that, while an amount is being entered into one storage device under control of the keys, the amount previously entered into the other device is transferred to the accumulator.

A more specific object of the invention is to provide an improved data storage device which is of improved construction and which embodies novel features of operation.

A still further object is to provide a multiple digit storage device with mechanism automatically operative upon completion of an entry therein for causing the entry to be transferred to an accumulator, and in which novel selectively settable devices are provided to cause the transferring to take place after any desired number of digital positions of the storage device have been set or controlled.

A further object is to provide an improved keyboard mechanism wherein the operation of any key closes a contact and the improved mechanism is provided for controlling the period of time during which the key operated contacts remain closed.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a central section through one of the storage devices.

Fig. 2 is a view similar to that of Fig. 1 showing certain of the parts in moved positions.

Fig. 3 is a transverse section of one of the storage units, the section being taken substantially along the lines 3—3 of Figs. 1 and 4.

Fig. 3a is a plan detail of the restoring slide, the

view being taken in the direction of the arrows 3a—3a of Fig. 4.

Fig. 4 is a section looking in the same direction as the view of Fig. 1, this section being taken just inside the side frame as indicated by the lines 4—4 of Fig. 3.

Fig. 5 is a view looking in the direction of lines 5—5 of Fig. 1.

Fig. 6 is a detail of the operating clutch mechanism of the storage unit showing the clutch in its tripped or engaged position in readiness to drive the moving parts of the unit.

Fig. 7 is a sectional view taken through the keyboard mechanism showing the contacts operated by keys.

Fig. 8 is a view showing certain of the parts of Fig. 7 in moved position, specifically, one of the keys is in depressed position to show the manner in which it effects the closure of certain contacts.

Fig. 9 is a detail of a bail operating magnet, looking in the direction 9—9 of Fig. 11.

Fig. 10 is a further detail of a key operated contact, this section being along lines 10—10 of Fig. 11.

Fig. 11 is a view of the keyboard and constitutes a view looking from the left at the mechanism of Fig. 7.

Figs. 12a and 12b placed one above the other 30 in the order named constitute a wiring diagram illustrating the controlling circuits between the keyboard, storage units and accumulator.

Fig. 13 is a chart showing the time of operation of certain of the cyclically operable contact devices.

The keyboard

Referring to Figs. 7 and 11, there are provided ten keys 10, one for each of the digits, arranged in three rows as shown in Fig. 7. The keys are supported between plates 11 and 12 in which they are suitably mounted for vertical reciprocation and normally held in their upper position by springs 13. A usual form of roller disk interlock device generally designated 14 is provided for co-operation with extending arms or tongues on the keys, so that only one key may be depressed at a time.

Depending from each key is a hook 15 freely pivoted at 16, which lies between a fixed cross-bar 17 and a pivoted contact arm 18. The arm 18 is normally urged in a counter-clockwise direction by a spring 19, so that its upper end presses against an insulating block on the hook 15 to urge the hook against the fixed bar 17. Upon depre-

sion of the key 10 from the position shown in Fig. 7 to that shown in Fig. 8, the hook 15 enables the spring 19 to rock contact arm 18 counterclockwise to close a related pair of contacts 20. If the key is now released, the hook 15 engages under the cross-bar 17 and holds the key in its lower position.

The arm 18 under the influence of the spring 19 as shown in Fig. 8 has rocked the hook 15 clockwise to cause the lower end of the hook to engage and rock a ball 21 counterclockwise from the position shown in Fig. 7 to that shown in Fig. 8. This ball is pivoted on a rod 22 and abuts two pairs of normally open contacts designated 23 and 24 (see Figs. 10 and 11) to cause closure of these two pairs of contacts. In line with contacts 23 is a pivoted spring pressed hook 25 (Figs. 7 and 8) which, when the contacts are closed by ball 21, will snap over the longer blade of the contacts and latch them in closed position as shown in Fig. 8.

The downward movement of key 10 also causes it to engage and rock a ball 26 pivoted at 27 from the position shown in Fig. 7 to that of Fig. 8. This ball has a depending finger 29 normally engaging a spring pressed pivoted latch 30. With the ball 26 rocked clockwise by key 10, the latch 30 is free to rock counterclockwise under the influence of its spring to the position shown in Fig. 10, where it engages the under side of the transverse part of ball 21. Thus, upon depression of the key 10 the parts are in the position shown in Fig. 8 with the selected pair of contacts 20 and the contacts 23 and 24 closed. These contacts effect the completion of circuits, as will be explained in connection with the circuit diagram.

Upon closure of contacts 23, a circuit will be completed to a so-called "timing magnet" 31 which, upon energization, rocks its armature 32 clockwise as viewed in Fig. 9 and, through an arm 33 secured thereto which engages ball 21 causes the latter to rock clockwise about its pivot rod 22. The effect of this is to cause opening of the contacts 20 and 24 while contacts 23 remain latched. The opening of contacts 20 is effected through the intermediary of hook 15 which incidentally is disengaged from bar 17, so that it is free to return to its upper position. The ball 21, as it approaches its initial clockwise position will through extending arm 34 (Fig. 7) engage and rock the latch 25 out of cooperation with the longer blade of contacts 23, so that these contacts may open at such time. By this means there is a slight difference in time of opening of contacts 24 and 23, whereby the latter contacts open slightly after the former.

If upon the energization of magnet 31 key 10 is held depressed, the latch 30 (Fig. 10) will rock still further in a counterclockwise direction to prevent the ball 21 again moving counterclockwise when magnet 31 becomes deenergized and unwanted repeated operation of contacts 20 is thus prevented. When the key 10 is released to move to its uppermost position, it allows the ball 26 to rock counterclockwise under the influence of its spring and through the depending arm 29 latch 30 is rocked out of latching engagement with the ball 21.

Storage unit

Referring now to Figs. 1 and 3, the mechanism of the storage unit is supported between two side frames designated 40. Between these frames are eight slides 41 insulated from each other

and from the framework. These slides are supported and guided by an upper cross-bar 42 and a similar lower bar 43. For each bar there is a tension spring 44 anchored at 45, which normally holds the bar in the position shown in Fig. 1, where its right end abuts a cross-bar 46. The direction of pull of spring 44 is such that the bar is urged downwardly and toward the right. For each slide 41 there is a cam lobe 47 rotatable on the shaft 48 and spaced so that, as the lobes rotate counterclockwise, each in turn will engage a stud 49 on its associated slide to move the latter from the position in Fig. 1 to that of Fig. 2. The action is such that, as the lobe 47 engages the stud 49, the slide 41 is first moved toward the left until block 50 in the slide engages the inclined surfaces of the bars 42 and 43, after which the slide moves obliquely upward and toward the left, in which position a slide is shown in Fig. 2.

The cam lobes 47 are rotated in steps, each step being equal to the angular distance between successive lobes so that, for the first step in the operation, the #1 lobe moves from the position of Fig. 1 to that of Fig. 2, where it comes to rest with the parts positioned as shown in Fig. 2. In the next step of operation the #1 lobe moves to the position designated 8 in Fig. 1, while the #2 lobe moves to the position that the #1 lobe occupies in Fig. 2, thus in turn moving the second slide 41 to its upper left hand position while at the same time the #1 slide returns to its lower right hand position. The continued counterclockwise stepping of the lobes 47 will thus in turn move each slide 41 from its lower right hand to its upper left hand position.

Carried by each slide 41 is a series of ten brushes or contactors 51 of resilient spring wire, each bent in an arc around three ears 52 formed in the slide 41. Each contactor 51 is longitudinally shiftable with respect to the slide between a lower and an upper position, with the tension of the wires bearing against ears 52 serving to hold the wires in either position. The wires in their lower position may be said to be in "unset" condition, and any wire in its upper position may be said to be in its "set" position, with the particular wire set indicating the digit entered or "set" on the slide. Thus, in Fig. 1 the wire 51 farthest to the right is shown in its upper position to represent a setting of 1 on the slide shown.

Extending transversely across the slides is a series of fixed common contact bars 53 adjacent to each of which is an insulating bar 54. Also extending transversely across the slides 41 and beneath the same is a series of pivoted insulating bars or plates 55 which are pivoted at their lower extremities as shown in Figs. 4 and 3a, on pins 55a extending into suitable pivot holes in the opposite sides plates 40. For each of these pivoted bars there is a magnet 56 and a cooperating armature 57 pivoted at 57a and extending upwardly into engagement with the related bar 55, so that upon energization of magnet 56 its armature is rocked clockwise about its pivot 57a and related bar 55 is swung in a like direction so that, for example, with the 1 magnet 56 energized, the 1 bar, i. e. the one farthest to the right, is moved to the position shown in Fig. 2. The upper extremity of armature 57, when the armature is rocked by its magnet 56, presses against the related plate 55, causing the plate to rock about its pivot pins 55a and shift from the position of Fig. 1 (for the right hand plate 55)

to position of Fig. 2. The space between adjacent plates 55 is sufficient to enable the necessary rocking movement of the armatures 57. The armatures 57 and related magnets 56 are arranged in three rows as shown in Fig. 5, so that in each row the armatures are spaced apart the distance between four plates 55 as seen in Fig. 1, where one of the rows is shown.

Positioned above the bars 55 (see Fig. 4) is a supporting bar 58 (see also Fig. 3) containing spring pressed detenting plungers 59 which bear against the bars to resiliently hold them in either their clockwise or counterclockwise positions. The bar 55, when rocked from the position of Fig. 1 to that of Fig. 2, remains in such latter position while the slide 41 returns to its lower right hand position and, as it moves to such position, the lower end of the related brush 51 strikes against the upper edge of the rocked bar intercepting the movement of the brush with the slide, and as a result the brush becomes longitudinally displaced on the slide with its upper end extending up sufficiently to make electrical contact with the related cross-contact bar 53 to thereby establish an electrical contact between the slide 41 and a selected bar 53, when the slide is down.

In other words, with slide 41 in its up and to the left position, as in Fig. 2, the rocking of a bar or plate 55 to its upright position will bring the upper edge of the plate into the path of movement of the lower extremity of the related brush 51 and, as the brush moves in its return path, it will be intercepted and retarded against full movement with its supporting slide 41. As a result, when the slide reaches its restored or down and to the right position, the brush 51 will have been displaced thereon as shown in Fig. 1 for the #1 brush. In brush positions where plates 55 are not rocked but remain in their oblique positions, the brushes 51 simply pass by the upper ends of the plates without being disturbed thereby.

After the slide 41 has returned to its initial position, the rocked bar 55 is restored to its initial position by one of the lobes of a cam 60 (Figs. 3, 4 and 6). This cam is integral with the lobes 47 and in its movement engages and rocks an arm 61 pivoted at 62 whose upper end has pin and slot connection with slider 63 mounted for horizontal movement. Depending from the slider 63 are fingers 64 (see also Fig. 3a), one for each of the bars 55, which when the slider is moved toward the left as viewed in Figs. 3 and 4 will engage and rock bar 55 and return it to its normal position, where it is held by the detenting plunger 59.

Alternate fingers 64 extend straight down in the plane of slider 63 while the remainder are offset to extend down in a plane parallel to slider 63, and the plates 55 are provided with notches 55b to afford clearance for the movement of the fingers. Specifically, the finger 64 which engages a particular plate 55 normally extends into a notch 55b of the plate 55 next to the right, and it will, of course, be appreciated that if fingers 64 were made narrower, that is, about half the width shown in Fig. 4, they could be arranged in a single plane and the notches 55b eliminated.

When a slide upon which a setting has been made is next operated, the positioned brush thereon is first shifted back to its normal or lower position, that is, the former entry is first reset. This is automatically brought about during the

movement of the slide to its upper left hand position. In moving to this position the upper end of the brush 51 contacts the lower surface of the cross-bar 54, while the slide moves upward. This, by restraining the brush, effects the longitudinal displacement thereof downwardly to its normal position. Thus, for each slide there may be said to be a succession of events, that is, an entry on a slide is first reset while the slide moves to its upper left hand position. While the slide is in such position a selection is made for the next setting thereof by the rocking of an appropriate bar 55, and then as the slide returns to its initial position the selected brush "takes a reading" from the shifted bar 55 and makes electrical connection between the slide 41 and the appropriate bar 53. Thereafter, the slide 55 is rocked back to its initial position. The bar 55 in returning to its initial position also serves to restore the armature 57.

It is quite apparent from an inspection of Figs. 1 and 2 that, when any slide 41 is moved to its upper left position of Fig. 2, the remaining slides are in their lower right position of Fig. 1, and 10 rocking of a bar 55 to its upright position will bring the upper end of such rocked bar 55 just up to the lower ends of the brushes 51 of the slides that remained in the position of Fig. 1. These 15 brushes are accordingly not disturbed, nor do 20 they interfere with the rocking of a selected bar 55.

The mechanism for rotating or stepping the slide operating lobes 47 will now be explained. Extending through the set of cams is the shaft 35 48 which through any suitable driving mechanism may be caused to rotate constantly. The shaft 48 is provided with teeth 65 which lie in the plane of a pair of pawls 66 (Fig. 6). These pawls are pivoted on studs 67 secured in the cam 68 40 which, as explained, is integral with the slide operating lobes 47 and is freely rotatable on the shaft 48. Also integral with cam 68 is a cam 69 (Fig. 4) and between these two cams is a ring 69 which is slightly rotatable with respect to the cams 60 and 68, being supported by the 45 studs 67 which extend between the two cams. The ring 69 has a pair of ears 70 which engage the pawls 66 as shown in Fig. 6, the pawls being bifurcated at their pivoted ends to accommodate the ears 70. It will be noted from Fig. 6 that, if ring 69 were rotated clockwise with respect to cam 68, ears 70 would rock the pawls 66 counterclockwise out of engagement with the teeth 65.

55 The parts 68 and 69 are normally held in displaced relationship as indicated in Fig. 4, that is, the cam 68 is held in position by a spring pressed detent arm 68a and the ring 69 is held in a clockwise direction with respect to cam 68 by the hooked end 71 of a lever 72 which is pivoted at 73. With the parts in the position shown in Fig. 4, shaft 48 rotates freely without effecting the operation of any of the other parts. Magnet 74, when energized, will rock its armature 75 and thereby release arm 72 so that under the influence of its spring 76 it will rock clockwise from the position of Fig. 4 to that of Fig. 6 to release ring 69, whereupon the pair of springs 77 will be free to rock the pawls 66 into engagement with teeth 65 and at the same time rotate ring 69 70 slightly in a counterclockwise direction to its relative position with respect to cam 68 as shown in Fig. 6. The slight rotation of ring 69 is caused by the clockwise rocking of pawl 66 whose point of engagement with ear 70 rocks about center 77

and the arc through which this point travels is the distance that ear 70 and its ring 69 are moved. In this manner a clutching action is effected between the constantly rotating shaft 48 and the cams 60 and 68 as well as the slide operating cam lobes 47, and the cam lobes will be advanced one step or $\frac{1}{8}$ of a revolution. During this step of movement, a lobe of cam 68 (Fig. 4) will engage an extension on arm 72 rocking it back to its latching position and shortly thereafter another lobe of the same cam will rock the armature 75 back to its normal position so that, near the completion of its step of movement, the ring 69 will again be engaged by hook 71 and displaced with respect to cams 60 and 68, which advance the full step, to be held in such advanced position by the detenting lever or finger 68a. Repeated energization of magnet 74 will step the slide operating cams around, step by step.

Referring to Fig. 1, the position of the cams 47 with respect to the remainder of the mechanism may be termed their "home position" for purposes of further explanation, and with the cams in this position one of the lobes 47 engages and causes the shifting of a set of contacts which are designated 78, 79 and 80 and also contacts 78a and 79a adjacent thereto as shown in Fig. 3. These contacts are in the positions shown in Fig. 1 when the unit is in its so-called "home position" and are in their reversed condition at other times.

As is apparent from Figs. 1 and 2, the upper blade of contacts 78 and the lower blade of contacts 79 have a slight overthrow so that, when their common blade shifts from the position of Fig. 1 to that of Fig. 2, contacts 78 make before contacts 79 break. When the common blade shifts from the position of Fig. 2 to that of Fig. 1, contacts 79 make before contacts 78 break.

Referring now to Figs. 1 and 2, there is mounted at the left end of each storage slide 41 a contacting brush designated 82 which extends beneath a contact plate 83 (see also Fig. 5). Spaced from plate 83 and insulated from it are eight individual contact elements 84, one for each of the column positions of the storage unit and which are each positioned to be contacted by a related brush 82 when the slide 41 is moved from the position of Fig. 1 to that of Fig. 2. In other words, the brushes 82 on the slides are normally in lower position where the brushes are out of contacting relationship with the plates 83 and 84. When any slide is in its upper entry receiving position, the related brush is moved up to make an electrical connection between the common plate 83 and the individual element 84 related to that slide. The brush 82 and plates 83, 84 are used to ascertain when entries have been made in a selected number of slides 41. These parts are shown diagrammatically in the circuit diagram (Fig. 12b), where the common plate 83 is shown as a series of common contacts and the individual plates 84 are separately wired to plug sockets. Structurally, the socket is formed in plate 84 itself by a pair of ears bent in its upper end (see Figs. 1 and 5). If it is determined that, for example, six slides only are to be used, then a connection 99 (Fig. 12b) is made to the plate 84 associated with the sixth slide 41. As entries are made in the slides for the 1, 2, 3, 4 and 5 positions, their brushes 82 are moved to electrically connect common plate 83 to the related plates 84 but such connections have no effect. When the 6 slide, however, is

moved and its brush 82 makes the electrical connection, a circuit is completed to energize a relay R1 as will be traced in connection with the explanation of the circuit diagram.

- 5 It may be pointed out that the slides 41 are insulated from each other and from the supporting framework, and that current is supplied thereto through spring 44 and the spring anchor 45 (Fig. 1), which latter is a plug socket secured in an insulating cross bar as shown. In the circuit diagram (Fig. 12a) the slides 41 are shown diagrammatically as vertical lines terminating in plug sockets from which connections 106 are made to sockets of contacts designated 105 MR1a. The cross bars 53 are shown as double horizontal lines and the positions in which a slide 41 is electrically connected to a bar 53 is represented by a circle at the point of intersection.

Accumulator

The accumulator is of the well-known form known as the "Hollerith" accumulator and is diagrammatically shown in Fig. 12a, where this device is generally designated 85 and the entry controlling magnets are indicated at 86. As is well known, when these magnets are energized at differential times to represent various digits, they effect clutching action between rotating parts to advance accumulator or indicator wheels indicated at 87 to positions representing the amount entered into the accumulator. The driving mechanism for the accumulator is diagrammatically represented as being from a constantly rotating shaft 88 to which the drive gear 89 of the accumulator is coupled upon energization of the clutch magnet 90. When magnet 90 is energized, clutch mechanism generally designated 91 connects the gear 89 for rotation by the shaft 88. Through the usual gears 92, shaft 88 also drives a Geneva mechanism 93 which in turn drives the usual reset shaft 94. A magnet 95 upon energization will actuate a clutch designated 96 and cause the accumulator to be reset or restored to home position.

Circuit diagram

Referring now to Figs. 12a and 12b, current is supplied to a pair of main lines 97 and 98. Operations are commenced by first effecting a resetting operation of the accumulator to insure that it is clear and by also effecting a clearing or restoration of storage unit #1 which is the first to receive an entry. As a preliminary, it is determined how many columns of storage units are to be employed, and for the present explanation it will be assumed that six columns are to receive entries and the other remaining two are not. Accordingly, plug connections 99 and 100 in Fig. 12b are made from plug sockets 101 and 102, respectively, to the contact elements 84 related to the sixth columnar position of the two units. The circuits involving these plug connections will be pointed out later.

As stated above, a reset operation is first carried out. This is initiated by closure of a pair of reset contacts designated 103 in Fig. 12a which complete a circuit through the reset magnet 95 and also through a relay magnet R4. As a result, the clutch 96 is engaged and the indicating wheels 87 of the accumulator are restored to home position if they are not already in such position. It may be explained at this point that driven from the gear 89 (Fig. 12a) are a number of contact operating cams suffixed CC and a contact cam CB which make one revolution for each

cycle of operation of the accumulator. The timing of the contacts controlled by these cams is indicated in Fig. 13 where there is also indicated the timing of an emitter which is also operated from the driven gear 89 when the accumulator is operated. In the circuit diagram two storage units are represented, both of which are exactly alike, structurally. In Fig. 12b the entering magnets 56 are shown for the two units and designated unit 1 and unit 2. A single set of keys 10 has its contacts wired to both sets of magnets for concurrent energization of both related magnets for any digit, although as will be pointed out hereinafter the sets of magnets are alternatively effective to enter the data in their respective storage units. In Fig. 12a are shown the two readout devices 41, 53 designated unit 1 and unit 2, and these alternatively complete circuits to a single set of accumulator magnets 86 as will also be explained. Other contacts such as 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 19

the common plate 83 and the individual conductor 84 of this column, which is the one in which the plug connection 99 has previously been made. Therefore, when the 8 key 10 is now operated to make the sixth and last entry into the unit, the clutch circuits as traced before will be completed. In addition, there will be a further circuit at this time traceable from line 97, contacts R3b, and 24, the common plate 83 of unit #1, brush 82 of column 6, contactor 84, plug connection 99, plug socket 101, relay magnet R1 to line 98. R1 will close its contacts R1f to provide a circuit through its holding coil traceable from line 97, cam contacts CC4, contacts R1f, holding coil of magnet R1 to line 98. This circuit will be held until the amount now entered in storage unit #1 has been transferred to the accumulator. Since no entries are to be made in the 7 and 8 columns of the storage unit, these columns are automatically passed over and the unit brought back to home position in the following manner.

Relay magnet R1, when energized, shifts its contacts R1a, and completes a circuit from line 97, contacts R1a (left), contacts R4a (right), contacts 18a, magnet 74, to line 98. Therefore, this clutch magnet 74 is held continuously energized until the unit has been stepped to its home position wherein contacts 78a open to break the circuit leaving the unit in this position. The energization of magnet R1 also serves to bring storage unit #2 into its starting position with the first column in entry receiving position. This is effected as follows. The magnet R1 closes a pair of contacts R1c and completes a circuit from line 97, contacts R1c, R2b (right), contacts 79a of unit #2, clutch magnet 74 of unit #2. This impulse to the magnet moves its column 1 slide to the upper position and also opens the contacts 79a.

The speed of operation or rate of rotation of the cam unit is such that unit #1 is advanced to its home position before the operator presses the next key to enter the first digit of the second amount. Further than this the speed at which the keys may be operated is limited by the interlocks described, including key release magnet 31, so that even where the plug connections are adjusted for single digit entries, the seven unused slides will be skipped and the unit brought to home position between successive operations. In practical operation also, there is generally a pause between successive amount entries which increases the allowable time interval. Such interval is, however, not critical so that, if the stepping operation proceeded at a slower rate, the operation of an entering key before the unit had reached home position might effect a digit setting in one of the unused slides in addition to the setting in the proper slide of the alternate unit. This would have no effect on the operation, since the unused or skipped slides are not connected for control of the accumulator, and any such setting would be erased following the next amount entry in that unit.

From this point on the operator depresses the keys 10 to enter a second amount into unit #2 which, for example, let us assume is the amount 647325. The circuits previously completed from the key contacts to storage unit #1 clutch magnet 74, through wire 104, will now not be completed because the relay magnet R1 is energized and the contacts R1a are shifted to break the circuit to wire 104. Instead, the key contact circuits are traceable from line 97, contacts R3b,

24, wire 104 to contacts R2a (right), contacts R4b (right), 78a of unit #2, clutch magnet 74 and line 98. Repeated operation of the appropriate keys will effect the entry of the amount mentioned into the storage unit #2.

The magnet R1 closes a pair of contacts R1d (Fig. 12a) which complete a circuit from line 97, contacts CC1, contacts R1d, contacts 80 of unit #1, the accumulator clutch magnet 90 to line 98. This circuit is completed when unit #1 is back in its home position, wherein the contacts 80 are closed and with magnet 90 momentarily energized the accumulator will effect a cycle of operation during which the cam contacts and emitter operate.

The magnet R1 also closes a pair of contacts R1e to complete a circuit from line 97, through contacts CC2, R1e, magnet MR1 to line 98. Magnet MR1 closes its contacts MR1b to provide a holding circuit through cam contacts CC3 and the holding coil of the magnet. It also closes a group of contacts designated MR1a to enable the completion of transfer circuits from storage unit #1 to the accumulator magnets 85, during this cycle of operation of the accumulator. In Fig. 12a the grid formed by the bars 53 and slides 41 is diagrammatically represented and the circles at the points of intersection indicate the positions in which brushes have been adjusted in accordance with the setting of the amount 153028 previously entered. As the emitter and cam contacts now rotate, parallel circuits are completed through all the columns of the unit to energize the accumulator magnets at times appropriate to the entry of the various digital values into the accumulator. A representative circuit is traceable from line 97, contacts CB, brush of emitter designated E, wires 105, common bars 53, the brushes 51 in the positions designated, slides 41, plug connections 106, contacts MR1a, wire 107, magnets 86 to line 98. With magnets 86 thus energized at differential times, the accumulating elements will be advanced in the well known manner. After the entering portion of the cycle, contacts CC3, open to deenergize magnet MR1 and contacts CC4 also open to deenergize magnet R1. This transfer into the accumulator from storage unit #1 takes place while the operator is making an entry in unit #2. Assuming that the transfer is completed before the second amount is entered into storage unit #2, then when the entry is made in the sixth column of this unit a circuit is completed similar to that traced for unit #1 which energizes the relay magnet R2 through the plug connection 100 made to the sixth column conductor 84 of unit #2. This magnet in turn closes its contacts R2f to provide a holding circuit through cam contacts CC5. Now magnet R2 closes its contacts R2d so that the accumulator clutch magnet 90 is energized through the circuit from line 97, contacts CC1, R2d, contacts 80 of unit #2 when this unit has been advanced to its home position, magnet 90, to line 98.

If the transfer is not completed from unit #1 before a new amount is set in unit #2, magnet R2 is energized while R1 is still energized and is held by a circuit through contacts R2f and CC5 and also by a parallel circuit through R2f and MR1c. When contacts CC4 and CC5 open together magnet R2 remains energized over the period that CC4 and CC5 open and, when CC5 closes again, the first holding circuit is again established so that later, when contacts CC3 open to deenergize magnet MR1 magnet R2 remains

70 78

energized and its contacts R2d (Fig. 12a) will enable contact CC1 to again energize the accumulator clutch magnet 80. Likewise if the ensuing transfer from unit #2 is not completed before a new amount is set in unit #1 magnet R1 will be energized and will be held through contacts MR2c to bridge the open period of contacts CC4.

Advance of unit #2 to home position after a six column amount has been entered is controlled by a circuit from line 97, contacts R2a (left) which are now closed, R4b (right) contacts 18a of unit #2, magnet 74 to line 98. This circuit is broken when the unit reaches home position and opens contacts 18a, at which time also the contacts 80 of unit #2 close, so that the accumulator clutch magnet may be energized. Relay R2 closes its contacts R2c (Fig. 12) so that, when relay R1 is deenergized, a circuit is completed from line 97, contacts R2c, R4b, contacts 19a of unit #1, magnet 74 to line 98. Thus, magnet 74 of unit #1 is stepped to its starting position in readiness to receive further entries, it being remembered that, whenever a slide is moved upward, any previous entry therein is automatically erased.

Thus, it is seen that each storage unit receives digital entries up until the selected columnar position is reached, at which time it is automatically advanced to home position and upon reaching such home position a cycle of operation of the accumulator is initiated during which cycle the amount in the storage unit is transferred to the accumulator. Each unit in turn also through its related relay R1 or R2 conditions the other unit to receive a new amount by advancing the other unit from its home position to its starting position. In the case of storage unit #2, the relay magnet MR2 is energized through the relay contacts R2e, and through circuits paralleling those which energize the relay magnet MR1.

The cycle of operation in the accumulator is very rapid so that, where the amounts entered are of more than two or three positions, the transfer from the unit is completed and the unit in readiness to receive a new amount before the entry is completed into the other unit.

Where smaller numbers are dealt with, that is, where the plug connections 99 and 100 (Fig. 12b) are made in the lower ordered columnar positions of the slides, it may be that the amount is not fully transferred from the storage unit at the time when a new amount is to be entered therein. This would be indicated by the energization of both magnets R1 and R2. For example, with an amount entered in storage unit #1 and contacts CC4 still closed when the amount is fully entered in unit #2, magnet R2 would then also be energized while magnet R1 is still energized. With magnet R1 and R2 energized, a circuit is traceable from line 97, contacts R1c, R2b (left), relay magnet R3 to line 98. A parallel circuit also extends through a signal lamp 108 which indicates to the operator that neither storage unit is in readiness to receive the next entry. Magnet R3 opens its contacts R3b so that the circuit to the key contacts is interrupted. Upon completion of the accumulator cycle, either magnet R1 or R2 will be deenergized, deenergizing the magnet R3, so that subsequent key operation will enter the next amount into the appropriate storage unit. It will be observed that, when any given number of columns of a unit is selected to

receive entries, there must be one entry made in each of the selected columns.

If the operator depresses a key while the signal lamp 108 is illuminated, this key will be latched down preventing further key depression because of the mechanical key interlock. Such depression, as explained, will close contacts 23 whose normal function is to energize the keyboard magnet 31 which it can not now do, since contacts R3a are shifted to open the circuit to magnet 31. Instead, a holding circuit is now set up from line 97, contacts 23, contacts R3a (right), release key contacts 109, holding coil of magnet R3 to line 98. Accordingly, if the key is depressed with the signal light on, such key is latched down and the circuit to the digit bail magnet 56 is not completed nor to the unit clutch magnet 74. The operator must wait until the signal light is extinguished by deenergization of either magnet R1 or R2 before depressing the release key to open contacts 109. When contacts 109 are opened magnet R3 becomes deenergized to permit contact R3b to close and operation will resume in a normal manner by completion of the circuits through magnets 56 and 74.

The relay magnet R3 is a comparatively slow acting relay, allowing time for the keyboard magnet 31 to operate in the event both magnets R1 and R2 are both energized, since as pointed out above such energization of the magnets R1 and R2 takes place upon closure of the key contacts 20 and such key, whose operation energized magnet R1 or R2, would be the one representing the last digit of the amount, so it is necessary to release this key before the concurrent energization of both magnets can disable the circuit for the magnet 31. After the last amount has been entered in a storage unit and transferred, these last amounts remain set in the storage unit and will be cleared when subsequent entries are made.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In combination, a storage mechanism having multiple columns of entry receiving elements, an entry receiving device, transferring means for concurrently transferring entries from the elements of the storage mechanism to said device, operating means for said transferring means, a set of keys, means controlled thereby for effecting entries into said columns of storage mechanism elements in successive order, each key operation effecting an entry in one column of elements, settable means for predetermining the number of columns of elements, to receive entries, means controlled jointly by said storage mechanism and said keys, when the predetermined number of columns of elements have received entries, for rendering said transfer operating means effective and further means controlled by said last named means for conditioning the storage mechanism to receive subsequent entries beginning with the first of the said predetermined number of columns of elements.

2. In combination, a pair of like storage mechanisms, each having multiple columns of entry

receiving elements, a single set of keys, means responsive to successive key operations for effecting entries into the columns of elements of one storage mechanism in successive order, presettable means, means controlled thereby and effective upon entry into a predetermined column of said one storage mechanism for causing said entry effecting means to respond to subsequent key operation to effect entries into the elements of the first column of the second storage mechanism, presettable means and means controlled thereby and effective upon entry into a predetermined column of said second storage mechanism for causing said entry effecting means to respond to subsequent key operations to again effect entries into the first column of elements of the first storage mechanism.

3. A storage mechanism for an accounting machine, comprising a plurality of columnar slides, each having a plurality of digit representing brushes thereon, each brush being displaceable on its slide from an active to an inactive position, means for effecting a reciprocation of each slide in turn, means effective during the forward stroke of each slide for returning the brushes thereon to their inactive positions and selectively operable means effective during the return stroke of the slides for causing the selective movement of any brush on the slide to its active position.

4. The invention set forth in claim 3 in which each brush comprises a flexed wire, the displacement thereof from one position to another is in the direction of the axis of the wire, the flexure of the wire serving to resiliently hold the same in position and in which a contact element is provided and located adjacent to the path of a brush, said means for effecting a reciprocation being constructed to effect relative movement between the contact element and brush during the return stroke of the slide to cause the displaced brush to engage the contact element and effect an electrical contact therewith.

5. In a storage mechanism for an accounting machine, a slide, means for reciprocating the slide, a contact wire supported on the slide for axial movement thereon between an active and an inactive position, a stationary stop located for engagement by one end of the wire during the forward stroke of the slide to shift the wire to its inactive position, a movable stop positionable in the path of the opposite end of the wire for engagement thereby during the return stroke of the slide to shift the wire to its active position and means for selectively controlling the operation of said movable stop.

6. In a device of the class described, a set of keys a pair of contacts for each key, closed thereby, a pair of contacts common to all keys, closed concurrently with the closure of the individual pair of contacts, a latch to hold the common pair of contacts closed, a magnet, a circuit completed therethrough by said common pair of contacts and means controlled by said magnet for opening the individual pair of contacts and concurrently releasing said latch to open the common pair of contacts whereby the period of closure of the pairs of common and individual contacts following their initial closure is determined by the time required to energize said magnet.

7. The invention set forth in claim 6 in which a second latch is provided and rendered effective upon initial energization of the magnet and upon continued operation of a key for latching the

common and individual pairs of contacts against reclosure upon deenergization of the magnet.

8. In a machine of the class described, a pair of storage units, a single set of keys, means controlled by said keys for effecting amount entries into said units digit by digit, alternate amounts being entered in alternate units, readout means for each unit, means settable for each unit for predetermining the number of digits to be entered in the related unit, an accumulator, means controlled by the settable means of each unit upon completion of an amount entry therein for causing its readout means to control said accumulator and means for preventing further entries into either unit until the related readout has controlled the accumulator.

9. In combination, a pair of storage mechanisms each having multiple columns of entry receiving elements, means for effecting entries into the columns of elements of one storage mechanism and then into the columns of elements of the second storage mechanism, presettable means for each mechanism, each settable in accordance with the number of columns of elements to be received by the related storage mechanism, readout control mechanism for each storage mechanism, readout mechanism controlled thereby, means controlled by the related presettable means for rendering the readout control mechanism of each storage mechanism effective upon completion of entries in the selected number of columns of elements thereof and while entries are made in the other storage mechanism and means for preventing entries into either storage mechanism until the entries previously made have been read out.

10. In a device of the class described, a series of storage slides each movable separately from a normal position to an entry receiving position, operating means for moving the slides, said means being intermittently operable to move the slides in successive order, means for initially controlling said operating means to cause positioning of all the slides in their normal positions, means controlled in part by said operating means when all the slides are in their normal position for moving the first slide in the series to its entry receiving position, settable elements on the slides, means for setting said elements, presettable means adjustable in accordance with a predetermined number of successive slides that are to have elements thereon set, a plurality of operable control devices, one for each of the digits, means effective upon operation of any control device when a slide is in entry receiving position for causing the setting of an element on said slide, and for causing said operating means to thereafter return said slide to normal position and move the next slide to its entry receiving position, and means jointly controlled by said presettable means and said operating means when elements have been set on said predetermined number of slides for causing an uninterrupted operation of said operating means to move all remaining slides in succession to their entry receiving position and then back to normal position.

11. In a storage mechanism, a plurality of slides arranged for movement in parallel planes, a shaft extending transversely across the slides, a series of like cams, one for each slide, arranged helically about said shaft and integral with one another and rotatable thereon to each in turn engage and move a related slide, stationary guides for the slides formed to guide the slides along

a fixed line and then in a direction at an angle to said fixed line when the slide is moved by its related cam, a spring on each slide for restoring the same, said guide causing the slide to retrace its path of movement when restored by said spring, positionable devices carried by the slides and adjustable thereon to represent data, and means for causing positioning of said devices during the restoration of the related slides.

12. The invention set forth in claim 11, in 10
which a constantly operating driver is provided

5 for said shaft, coupling means between the shaft and said cams, means to cause said coupling means to couple the cams to the shaft for step-by-step rotation of the cams, whereby a single slide is moved for each coupling operation, and means for causing the coupling means to couple the cams to the shaft for uninterrupted driving, whereby a plurality of slides will be moved in uninterrupted succession.

SAMUEL BRAND.
JAMES M. CUNNINGHAM.
